HANS HANSEN, OF KANSAS CITY, MISSOURI.

TELEPHONE-SWITCH MECHANISM FOR PREVENTING CORD-TWIST.

1,249,386.

Specification of Letters Patent. Patented Dec. 11, 1917.

Application filed March 12, 1917. Serial No. 154,123.

To all whom it may concern:

Be it known that I, HANS HANSEN, a subject of the Kingdom of Denmark, residing at Kansas City, in the county of Jackson, 5 State of Missouri, have invented certain new and useful Improvements in Telephone-Switch Mechanism for Preventing Cord-Twist, of which the following is a description, referring to the drawings which form a 10 part of this specification.

The invention relates particularly to switch mechanism located in the base of a desk telephone instrument and an improvement in the method of conducting the cord 15 wiring thereto whereby undesired twisting of such cord wiring is obviated, thereby increasing the life and usefulness of the cord.

In the desk telephone as now employed, 20 the cord wire leading from bell box enters the base of the telephone instrument through the same opening as the cord wire connecting to the receiver. These two sets of cords are very susceptible to becoming twisted and kinked making the use of the instrument unsatisfactory until the user has untwisted said 25 cords. My improved switch mechanism and allied parts give not only a much stronger switch connection and one less likely to get out of order but also overcome entirely the 30 objectionable cord twisting.

In the drawings, Figure 1. is a face view of the switch mechanism in the base of a desk telephone instrument, the base plate being removed to disclose same.

Fig. 2. shows a view of the bell box and cord from same entering the base of a telephone instrument and the cord from said base to the receiver.

Fig. 3. shows a portion of the base cover 40 of the telephone removed along the line X—X in Fig. 1. to disclose the view of the switch mechanism looking in the direction of the arrow.

Fig. 4 shows a portion of the base cover 45 of the telephone removed along the line Y—Y in Fig. 1. to disclose the view of the switch mechanism looking in the direction of the arrow.

Fig. 5 is a cross-sectional view of the two 50 ringed terminal seen in Fig. 1.

Fig. 6 is a side view of the end portion of the three ringed terminal seen in Fig. 1.

Fig. 7 is a perspective view of any one of 55 the five springs seen in Fig. 1; and having a platinum point formed thereon for contact purposes.

Similar numerals of reference indicate corresponding parts in all the figures of the drawings.

Referring to the drawings, at 10 is seen 60 the cord wiring leading from bell box 11 through hole 12 in base cover 13 of the desk telephone instrument 14. Through a hole 15 in 13 the cord wiring 16 connects to the receiver 17.

The terminal seen in Fig. 5 is composed 65 of the brass outer shell 18 adapted to receive the cord 16 through its end opening 19. The two wires contained in cord 16 are attached respectively to the screw terminals 70 20 and 21 respectively connected to the brass inserted portions 22 and 23 housed within the outer shell 18 in the manner seen in section, the parts 18, 23 and 22 being insulated as shown by the solid black portions of the 75 figure. The screw 20 passes through a copper plate 20^x held by two small screws 20^k, 20^l to the portion 22. This plate 20^x being insulated as shown in Fig. 5 from 25 and enables a good connection to be made in 80 attaching the wire to 20. The bore of shell 18 inward from 19 is preferably threaded in manufacture to more firmly grip and hold the cord 16 in desired coacting arrangement.

The terminal seen in Fig. 6 is similar to that 85 seen in Fig. 5, the cord 10 comprising three wires has one of said wires connecting with a screw terminal located within the shell 18^x on 22^x, a second wire is attached to a screw terminal on 23^x while the third wire is located with 90 in and in contact with the shell 18^x. It will be understood that the parts 22^x, 23^x and 18^x are likewise properly insulated in similar manner as described and shown concerning Fig. 5. Platinum rings 24 and 25 indicate 95 contact ring portions sleeved around the respective enlarged end portions of 22 and 23, Fig. 5. Likewise platinum rings 24^x and 25^x are arranged on 22^x and 23^x, likewise a third platinum ring 26 is arranged around 100 the end portion of 18^x, in Fig. 6.

27 indicates a plate attached to the upper under surface of the base cover 13. At 28 is seen a rear housing plate having feet 29, 29 held by insulated screws to the plate 27. 105 An insulation 29^x is introduced between feet 29 and plate 27. At 30 is a front housing plate having feet 31, 31 properly insulated and held by insulated screws to plate 27.

At 32 is a lever having its end insulated 110 at 33. This lever 32 is hinged at 34 in a hanger 35 suspended from 27. A rod 36

connected with the hook lever 37 is connected at 38 with lever 32. A coiled spring 39 bears against 27 and 32 as seen in Fig. 4.

Slots 40 and 41 respectively in the housing plates 28 and 30 permit the lever 32 to be passed therebetween.

Round holes are drilled through 28 at 42 and 43 of equal diameter to the rear end portions of 44 of 18 and 44^x of 18^x within 10 which holes said parts are rotatably housed as seen in Fig. 1. Likewise round holes in diameter equivalent to the portions 45 and 45^x of 18 and 18^x are drilled in the plate 30 at 46 and 47 and within which holes said 15 parts are rotatably housed as seen in Fig. 1.

Arms 48 and 49 project from the upper outer portions of 30. These arms are insulated as shown in black. Flat brass springs 50 and 51, similar to that shown in Fig. 7, 20 project from arm 48 and have their platinum points 52 respectively over and adapted to contact with platinum rings 24 and 25 on the terminal seen in Fig. 5 as housed in Fig. 1. Also, brass flat springs 53, 54, 25 55 project from arm 49 and have their platinum points 52 respectively over and adapted to contact with platinum rings 24^x, 25^x, 26 on the terminal seen in Fig. 6 as housed in Fig. 1. Each of these springs 30 are provided with insulated screw means for attaching them to their respective arms.

A wire 56 connects the terminals of springs 50 and 53, and a wire 57 connects the terminals of springs 51 and 54, these 35 wires pass under a plate 58 secured at 59 to 30. A wire 60 connected at terminal of spring 51 and a wire 61 connected to terminal of spring 55 lead to the transmitter 62. This arrangement of wiring performs 40 the same function as in common use in switch mechanism in other desk telephone switch mechanisms.

In my construction, when the receiver 17 is hung up on hook 37, the rocking lever 32 compresses spring 39 and the insulated end 45 of 32 bears against the outer ends of springs 50, 51, 53, 54, 55 removing their respective contact points 52 from the contact said points have been making with the 50 platinum rings adjacent thereto, thus cutting out the instrument to enable a ring to come in. This contact of springs 50 and 53 thus broken is illustrated by dotted line 55 position in Fig. 3, the new position of said springs being illustrated by solid line position. The cord 10 and its terminal bearings 44^x and 45^x are free to rotate in 12, 43 and 47 respectively and cord 16 and its terminal bearings 44 and 45 are free to rotate 60 in 15, 42 and 46 respectively thus entirely eliminating cord twist since the tension ordinarily given to such cords in twisting will now force the rotation of the parts instead.

When the receiver 17 is off the hook 37, 65 the spring 39 will operate whereby the por-

tion 33 will be removed from bearing against the flat springs 50, 51, 53, 54, 55 whence their points 52 will again spring down to contact some point on the periphery of the respective platinum rings 24, 25, 24^x, 25^x, 26 70 as previously described.

Such modifications may be employed as lie within the scope of the appended claims.

Having fully described my invention what I now claim as new and desire to secure by 75 Letters Patent is:

1. In a telephone switch, a terminal adapted to be wired to the telephone receiver, said terminal comprising an outer shell and two inner elements and insulations separating the component parts of said terminal, each inner element having a contact ring sleeved around an end portion of said element; and a second terminal adapted to be wired to the bell box mechanism, said terminal comprising an outer shell and two inner elements and insulations separating the component parts of said terminal, each of said inner elements and said shell having a contact ring sleeved around an end portion 80 thereof; both of said terminals being rotatably housed in bearings in the base of a telephone instrument, and means mechanically operated whereby contacts to both terminals may be closed for the purposes 85 specified.

2. In a telephone switch, a terminal adapted to be wired to the telephone receiver, said terminal comprising an outer shell and two inner elements and insulations 100 separating the component parts of said terminal, each inner element having a contact ring sleeved around an end portion of said element; and a second terminal adapted to be wired to the bell box mechanism, said terminal comprising an outer shell and two inner elements and insulations separating the component parts of said terminal, each of said inner elements and said shell having a contact ring sleeved around an end portion 105 thereof; both of said terminals being rotatably housed in bearings in the base of a telephone instrument; and five spring terminals, each being connected to telephone 110 instrument wiring, each of said spring terminals being insulated and attached to portions attached to the base of said telephone, each of said spring terminals having a contact point adapted to make and break contact with a specified contact ring carried by 115 one of said rotatable terminals when acted upon by means mechanically operated whereby contacts to both terminals may be closed or opened for the purposes as 120 specified.

3. In a telephone instrument, switch mechanism located in the base thereof, a bell cord wiring and a receiver cord wiring, each of said wiring entering the base cover 125 of said telephone instrument through an indi- 130

vidual hole and terminating in a terminal contact member rotatably housed in bearings attached to said telephone instrument, and means mechanically operating whereby contacts to both terminals may be closed for the purposes as specified.

4. In a telephone switch, a terminal adapted to be wired to the telephone receiver, said terminal comprising an outer shell and two inner elements and insulations separating the component parts of said terminal, each inner element having a contact ring sleeved around an end portion of said element; and a second terminal adapted to be wired to the bell box mechanism, said terminal comprising an outer shell and two inner elements and insulations separating the component parts of said terminal, each of said inner elements and said shell having a contact ring sleeved around an end portion thereof; both of said terminals being rotatably housed in bearings in the base of a telephone instrument; and five spring terminals,

each being connected to telephone instrument wiring, each of said spring terminals being insulated and attached to portions attached to the base of said telephone instrument; and a spring actuated lever hinged to a hanger attached to the base of said instrument and means connecting said lever to the receiver hook of said instrument, an insulation on the outer end of said lever; each of said spring terminals having a contact point adapted to make contact with a specified contact ring carried by one of said rotatable terminals when the receiver is off the hook, said insulated end portion of said spring actuated lever operating when the receiver is on the hook to break the contact between each set of spring contact points and contact rings in the manner as specified.
